METHOD AND MEANS FOR ATTACHING
FASTENING ELEMENTS TO FLEXIBLE
SHEET MATERIAL

Florence Kessler Slamon, New Brunswick, and
Donald C. Stanley, Elizabeth, N. J., assignors to
Industrial Tape Corporation, a corporation of
New Jersey

Application November 1, 1944, Serial No. 561,481

1 Claim. (Cl. 154—41)

1

This invention relates to an article and method for securing on cloth or similar material fastening elements such as buttons, hooks and eyes, and the like.

According to the invention, there is provided a sheet or tape coated on one side with a heat sensitive adhesive with a button or other fastening element secured to the sheet or tape on the same side. It is a simple matter with the improved article to apply the fastening element in place on a garment when it is originally made or in case of repair. The procedure merely involves slitting the fabric or other material to which the fastening element is to be attached, passing the fastening element through the slit, and bringing the adhesive side of the tape into contact with the material on the side opposite that which will present the fastening element. The application of heat and pressure to the back of the tape will render the adhesive sufficiently plastic to cause it partially to flow into the adjacent material. Upon cooling, a firm bond is established which, if a proper adhesive is used, will withstand numerous launderings and cleanings.

A better understanding of the invention may be had by referring to the accompanying drawing, wherein:

Fig. 1 is a perspective view of a piece of button tape incorporating the invention,

Fig. 2 is a perspective view of a piece of material to which a button has been applied using the improved tape in accordance with the invention,

Fig. 3 is an exploded view of the article shown in Fig. 1,

Fig. 4 is a transverse sectional view on line 4—4 of Fig. 2, and

Fig. 5 is a transverse sectional view illustrating the improved method of applying the fastening element to an article.

A base material, preferably a closely woven cloth 10 is coated with a layer of heat sensitive material 11 (Fig. 1). A button 12 or other fastening element is sewed or otherwise secured to the base material on its coated side. The base material 10 may present one or a plurality of fastening elements spaced as desired but preferably in the form of a tape with the fastening elements arranged along it at given intervals.

To apply the fastening element, in accordance with the invention, a slit 13, sufficiently long to accommodate the fastening element, is made, at the desired point in the cloth of the garment or

2

other article 14 (Figs. 2, 3 and 4). The button 12 is passed through the slit and the adhesive side of the base material 10 brought into contact with the side of the fabric opposite that which will present the button when the latter is finally secured in place.

The assembly is then placed button side down on a support 15, such as an ironing board, and heat and pressure applied to the back side of the tape material as by means of an iron 16 (Fig. 5). Preferably, the adhesive material is of a character such that the application of heat and pressure for a relatively few seconds only will suffice to soften the heat sensitive material and cause it to flow into the fabric so that upon cooling, there results a substantially permanent bond. Furthermore, it is unnecessary to bind the fabric along the edges of the slit 13 since the heat sensitive material, in conjunction with the tape backing prevents the fabric from fraying or unraveling.

It is preferred that the pressure be applied evenly over the entire surface of the tape backing. To insure this, it is recommended that there be inserted, between the fabric and the underlying ironing board during the pressing operation, a supporting element 17 which is recessed as at 18 to accommodate the button and which has an overlying portion 19 presenting a flat surface underlying the entire area of heat sensitive material.

Any suitable heat sensitive material providing a good bond and which will stand up under the conditions of service to which the fabric is exposed will suffice. Such a suitable heat sensitive material is disclosed in U. S. Letters Patent to de Forest Lott et al., No. 2,325,963, and is as follows:

40	Parts by Weight
A copolymer resin having 87% vinyl chloride and 13% vinyl acetate	70
Dibutoxy ethyl phthalate	25
Butoxy ethyl stearate	5
45 Calcium stearate	1.4

Heat sensitive material according to the above formula may be applied to the tape backing by well known methods of hot melt or solvent spreading after which the buttons are sewed or otherwise secured to the fabric on the coated side.

Although buttons have been specifically mentioned in describing the invention, it will be understood that other fastening elements, such as

hooks and eyes, snappers, etc., are included within its spirit.

The invention, therefore, is to be limited only by the prior art and the scope of the appended claim.

What is claimed:

The method of permanently applying a fastening device as, for instance, a button, hook and eye, and the like, to sheet material which comprises slitting the sheet material, passing the fastening device, previously secured to a different piece of sheet material on a side thereof coated throughout the area in the vicinity of the fastening device with a heat-sensitive adhesive, through the slit so as to present the fastening device at one side of the first-mentioned sheet material and by application of heat and pressure to the heat-sensitive adhesive, bonding the second-mentioned sheet material to the first-mentioned sheet material at the opposite side thereof 20 throughout the vicinity and along the edges of the slit therein.
